FLASH EVAPORATOR ROTOR

Herbert W. Stratford, Kansas City, Kans., assignor to Stratford Engineering Corporation, Kansas City, Mo., a corporation of Delaware

Filed Oct. 3, 1957, Ser. No. 687,952

1 Claim. (Cl. 159—4)

This invention relates to apparatus for dehydrating and degasifying liquids and refers more particularly to such apparatus wherein viscous liquid is introduced into a unique spray device from which it is discharged at high velocity in the form of greatly energized mist particles of micro dimensions into a zone of high vacuum.

This application is a continuation-in-part of my application Serial No. 373,340, filed August 10, 1953, now abandoned, and entitled "Method and Apparatus for Dehydrating and Degasifying Viscous Liquids." The invention is also an improvement over Patent No. 2,368,049 to Charles W. Stratford, entitled "Atomizing Evaporator," issued January 23, 1945.

Modern lubricating greases are generally mixtures of soaps and oil, the soaps being compounds of fatty acids and alkali earth metals, and the oils usually petroleum fractions. Both the soaps and oils normally include a large number of complex chemical components and frequently are relatively immiscible requiring intensive agitation and intimate mixing to produce a colloidal combination having a uniform consistency and stability with respect to oil separation, both in service and over prolonged periods of storage. This thorough dispersion required to produce a high quality grease normally entrains gases and vapors which are highly undesirable, both from the standpoint of chemical stability, appearance and sales appeal.

In the more modern grease plants, the mixing operations in certain stages of the manufacture are conducted under vacuum conditions to alleviate, insofar as possible, the occlusion and inclusion of gases and vapors into the grease. Greases requiring additional processing, such as milling, are aggravated by the difficulties mentioned since they acquire additional entrainment of air and gases or vapors during such operation.

The invention is designed for separating one or more volatile liquids or gases from liquids of higher boiling points under controlled uniform operating conditions of feed rate, temperature and absolute pressure. By introducing a preheated mixture of liquids into the inventive spray devices hereinafter described, from which the mixture is discharged at high velocity in the form of greatly energized mist particles of micro dimensions into a zone of high vacuum, the low boiling point constituents may be instantaneously flashed into vapor, the stripped particles of nonvolatile liquids impinging and coalescing, without entrainment, on the side wall of the evaporator and draining to the bottom for withdrawal.

Previously, viscous liquid distributing rotors have been employed in low pressure vessels to dehydrate and deaerate such liquids. I have discovered that if it is desired to employ a rotating spray device, such rotors must be of certain critical orifice form and size to adequately dehydrate and deaerate viscous liquids. Additionally, in combination with this critical orifice form and size, it is necessary, when the viscosity of the liquid to be dehydrated and deaerated passes a certain point, to employ a vessel of a certain form to adequately move the viscous liquid after discharging from the rotor downwardly to a removal point. If this form of vessel is not employed, the viscous liquid will merely pile up and clot on the sides of the vessel and will not be removable without opening the vessel. Such a construction involves firing the viscous liquid at high velocity against a surface which

2

is inclined upwardly and inwardly relative the vessel whereby to change the outward motion of the liquid into downward motion.

I have also discovered that viscous liquids may be dehydrated and degasified in low pressure vessels by employing nonrotating spray devices of critical orifice form and size. Such spray devices also advantageously are employed in vessels of certain forms. Nonrotating spray devices are less expensive, as well as simpler in construction than rotating spray devices.

Therefore, an object of the invention is to provide both rotating and nonrotating spray devices of the orifice form and opening size which will permit substantially complete dehydration and deaeration of liquids, including extremely viscous liquids, in a low pressure zone.

Another object of the invention is to provide vessels for employment with said spray devices of forms which permit the substantially complete dehydration and deaeration of very viscous liquids, said vessels shaped so as to change the high velocity outward movement of the liquid from the spray devices into downward motion, thus avoiding piling up and clotting of the viscous liquid on the sides of the vessel.

Another object of the invention is to provide both rotating and nonrotating apparatus for dehydrating and degasifying viscous liquids wherein, by controlling the feed rate, the feed temperature, the particle size and the absolute pressure within the inventive apparatus, it is possible to attain substantially any desired degree of separation of the volatile from higher boiling point liquids.

Another object of the invention is to provide such described dehydrating and degasifying apparatus applicable to the deaeration, dehydration and degasification of lube oils. In such use, three evaporators of the inventive type may be normally employed, the first serving for deaeration and dehydration of the oil charge, the second for sulphur dioxide removal after sulphuric acid treating, and the third for brightening the finished water-washed treated oil. The complete dehydration and deaeration of finished oil substantially improves its oxidation and color stability. Average cloudy lube oils rarely contain more than .05 percent of water and to dry these oils to an acceptable saleable brightness requires that the water content be reduced to .01 percent or less.

Another object of the invention is to provide dehydrating and degasifying apparatus applicable to dehydrate transformer oils to high dielectric specifications. This involves reducing the water content of the finished transformer oil to only a few parts per million.

Another object of the invention is to provide dehydrating and degasifying apparatus capable of removing all traces of low boiling point constituents from oils, along with moisture, absorbed air or other gases and including volatile malodorous compounds such as mercaptans.

Still another object is to provide such apparatus applicable to removing all detectable traces of alcohols often employed in the final processing of cosmetic or medicinal oils.

Another object of the invention is to provide dehydrating and degasifying apparatus which may be used for continuous product dehydration. Where several lube oils are to be blended continuously, with or without additives, the undehydrated components of the blend and additives may be charged to the inventive apparatus simultaneously. In passing through the apparatus spray device, all components of the finish blend are thoroughly dispersed, as well as dehydrated and deaerated to the required degree. With practically instantaneous water removal, no precipitation of salts from the additives occurs, even though the additives may be water sensitive. Such precipitated salts frequently cause an undesirable

70

haze which cannot be removed even by complete dehydration or deaeration.

Still another object of the invention is to provide dehydrating and degasifying apparatus useable for the dehydration and deaeration of stable emulsions or liquids of highly active surface characteristics, such as sulfonates or similar chemicals, with complete freedom from the usual troublesome frothing and foaming that occurs when conventional methods of dehydration are employed.

Another object of the invention is to provide dehydrating and degasifying apparatus suitable to remove low boiling point fraction hydrocarbons from lube oils treated with fine contact bleaching clay at high temperatures. The catalytic action of such clay often causes formation of hydrogen sulphide when organic sulphur components are present or it may crack the oil slightly thus forming such low boiling point hydrocarbons, the result being to lower the flash point of the product below specifications. The removal of such low boiling point fraction will restore the flash point.

Data on the dehydration of moisture-clouded lubrication stocks show that the water content of oils passed through the inventive apparatus may be reduced to a very minute quantity, the reduction being definitely less than is predictable under conditions of theoretically complete equilibrium. This phenomenon may be well explained by the fact that the vapor pressure of the micro-particles of liquid is much greater than is the vapor pressure of the same liquid in mass. In addition, the enormous composite liquid surface that is exposed in the zone of greatly reduced pressure promotes the efficient release of low boiling components or absorbed gases.

Other and further objects of the invention will appear in the course of the following description thereof.

In the drawings, which form a part of the instant specification and are to be read in conjunction therewith, an embodiment of the invention is shown and, in the various views, like numerals are employed to indicate like parts.

FIG. 1 is a side view with parts cut away and in section showing a vessel for employment with the inventive atomizing rotor to permit the dehydration and deaeration of extremely viscous liquids.

FIG. 2 is a cross section through the inventive rotor as mounted on a low pressure vessel.

FIG. 3 is a view taken along the lines 3—3 of FIG. 2 in the direction of the arrows.

FIG. 4 is a side view of a vessel for employment with the inventive spray head to permit the dehydration and deaeration of extremely viscous liquids.

FIG. 5 is a partly sectional view through a spray head assembly adaptable for use in the apparatus of FIG. 4, illustrating the particular spray head shown mounted in the FIG. 4 apparatus.

FIG. 6 is a side, partly sectional view of a second modification of the inventive spray head adapted to be used in a vessel for dehydrating and deaerating extremely viscous liquids.

FIGS. 1-3 show a rotating spray device employed in a low pressure vessel and this modification of the invention will be first described. FIGS. 4-6 show a nonrotating spray device employed in a low pressure vessel.

The operation of the inventive apparatus of FIGS. 1-3 consists in the impartation of high rotative velocity or energy to a fluid mixture by means of an atomizing rotor, said rotor consisting of a liquid accelerating disk and a shrouding disk spaced apart to form a narrow annular space therebetween with a narrow orifice of critical width defined at the periphery thereof. The fluid mixture to be separated is introduced to the annular space between the disks and is projected at high velocity from its periphery through the critical limited orifice. Separation of the flashable component from the mixture is effected by imparting sufficient energy to atomize the mixed fluid through the limited orifice in such a manner as to provide a relatively maximum surface per unit volume of the

fluid. The dispersal of the fluid takes the form of a continuous horizontal screen of high velocity greatly energized mist particles of micro dimensions extending from the orifice of the energizing atomizing rotor to the shaped inside wall of the enclosing vessel.

Referring to the drawings, and particularly to FIG. 1, at 10 is shown a vessel having an upper portion of its wall inclined both upwardly and inwardly relative the interior of the vessel, relatively vertical side walls, and a lower wall portion inclined both downwardly and inwardly relative the interior of the vessel. On top of the vessel 10 is a motor mounting 11 which supports the motor 12. Referring particularly to FIG. 2, opening 13 is formed in the top center portion of the vessel 10 and receiving rim 14 is fastened thereto by welds or other attachments 15. Mounting plate 16 is fixed within the rim 14 by bolts 17. The motor mounting 11 is welded or otherwise fixedly attached to the mounting plate 16 by attaching means or welds 18. Shaft 19 is a continuation of or fixed to the drive shaft of the motor 12 and may be driven in rotation thereby. Plate 16 has opening 20 centrally thereof. Support tube 21 is fixed to the plate 16 by bolts 22, extends therethrough, and has fitting 23 extending from one side thereof as well as recessed portions 24 at the lower end thereof. Pipe 25 is supported by bolt 26 relative to support tube 21 and surrounds shaft 19 with sleeve bearing 27 fixed to the inside surface thereof to maintain the shaft 19 in position relative thereto. Feed annulus 28 between the outside of the pipe 25 and the inner surface of tube 21 connects at its upper end with the bore of the fitting 23 to permit feed of the fluid to be flash evaporated or separated therefrom.

Accelerating disk 29, forming the lower surface of the atomizing rotor, has opening 30 centrally therethrough to receive a lesser diameter portion 19a of shaft 19 therethrough. Nut 31 engages the threaded bottom portion 19b of the shaft 19 and fixes the accelerating disk relative the end of the shaft. The upper central portion of the accelerating disk abuts the undersurface of the slightly greater diameter portion 19c of the shaft. The upper surface of the accelerating disk is also recessed as at 29a to permit positioning of the lower end of the pipe 25 in close association therewith. The accelerating disk 29 is preferably angled slightly upwardly in cross section as it extends outwardly from the central portion thereof. Shrouding disk 32, forming the upper portion of the atomizing rotor, is fixed by bolts 32a to accelerating vanes 33 which in turn are fixed to the accelerating disk 29. The shrouding disk 32 is preferably substantially horizontal, that is, fixed essentially at a right angle to the shaft 19. Shrouding disk 32 has upwardly extending central portion 34 which is recessed or indented to permit semiengagement of tube 21 and the disk and a portion of the tube 21 to overlie a portion of the top edge of the shrouding disk. The shrouding disk and the tube 21 are spaced one from the other to permit rotation of the shrouding disk relative the tube 21 without contact therewith.

The annulus or space between the accelerating and shrouding disks connects at its inward end with the annulus between the pipe 25 and the tube 21 to permit feed of liquids or fluids to be stripped or flashed into the rotating disk where the vanes 33 will hurl it through the orifice. The orifice 35 at the periphery of the two disks, to effectively operate to properly disperse the fluids, must be formed by two edges which are essentially vertically in line and not over one fifteen thousandths of an inch apart. I have discovered that if either the periphery of the shrouding disk or the periphery of the accelerating disk extends past the other or the orifice therebetween exceeds fifteen thousandths of an inch, the apparatus will not effect sufficient dispersal of the liquid or fluid to be stripped or flashed. The upward angling of the accelerating disk or, indeed, the relative angle of either of the disks relative the shaft 19, is not critical, provided the

peripheries of both disks are essentially vertically in line and the orifice is of an aperture in the range of two to fifteen thousandths of an inch. One one hundredth of an inch is about optimum gap for most greases.

Referring to FIG. 1, legs 36 support the vessel 10 and an opening is preferably positioned centrally of the bottom of the vessel with draw-off line 36a leading therefrom with pump 36b connected thereto. Vacuum line 36c draws preferably from the top portion of the vessel. Steam or any other inert gas may be supplied to the vessel through pipe 37 and is introduced beneath the atomizing disk through a hollow perforated ring 38.

In operation of the FIGS. 1-3 modification, the fluid to be flashed or stripped is introduced to the fitting 23 where it passes down the annulus 28 and into the space between the shrouding and the accelerating disks. In the throat of the rotor, the fluid is picked up by the vanes 33 and the rotation of the disk by the shaft 19 moves the fluid outwardly where it is projected through the orifice 35 in the form of mist particles of micro dimensions which travel from the orifice to impinge upon the upwardly and inwardly slanted portion of the vessel 10. The disk or rotor must be positioned so the particles impinged on the upwardly and inwardly inclined surface and not the vertical portions thereof so that the outward momentum of the particles may be transformed into downward momentum. The volatile constituents are completely evaporated from the finely divided energized mist particles during the traverse. The volatiles in the form of water vapor, gases and the like are withdrawn from the confined space within the vessel through vacuum outlet 38 which is connected to a vacuum head, not shown. The vacuum in the vessel is normally controlled within the range of one-half inch to ten inches of mercury absolute pressure depending upon the final water content or other volatile content desired in the fluid being treated.

I have conclusively established that an extension of the lip of either the shrouding or accelerating disk as in conventional rotors or the provision of an orifice of greater width than fifteen thousandths of an inch, with or without such extension, will prevent practical operation of the rotor and permit the accomplishment of none of the objects of the invention.

As an example of the effect of a lip, tests were conducted in a pilot plant. The original work was done with a rotor having a four-thousandths inch orifice (below the critical size limit set forth above) but with a one-half inch lip extension over which the discharge from the orifice passed. In this work it was possible only to reduce the moisture content of the feed stock to .008 percent when operating at one inch mercury absolute and at six inches of mercury absolute there was a moisture content in the product of .14 percent. These values were not considered to be sufficient to produce a commercial grade product. By removing the one-half inch lip and closing the orifice to .002 to .004 inch, it was possible to obtain at one inch mercury absolute operating condition, a product having only .0032 percent water. This value achieves the desired objects.

I attribute the remarkable results of my atomizing and dispersing rotor with aligned disk lips and critical orifice size to the elimination of shock waves from the rotor. Such shock waves appear when a lip is extended beyond the rotor, or when the orifice size is too great. Of course, when the orifice size is greatly excessive, there is no atomizing of the particles sufficient to permit stripping thereof of volatiles. However, even when atomization is effected by a reduction in the orifice size and the passage of the fluid to be stripped from the rotor to the vessel wall is in the form of particles and not a continuous film, the stripping is unsatisfactory unless the rotor lips are in line and the orifice is within the critical size.

Further evidence of the criticality of the alignment of the rotor lips and the orifice size is evidenced by the following data. The inventive apparatus was placed in operation as a grease polisher. A unit had a sixteen inch

diameter rotor which included a two inch lip on the rotor cover or shrouding disk. There was a one-sixteenth inch orifice clearance between the rotor and the rotor cover or the shrouding and accelerating portions of the disk

5 and, when operating with this rotor as originally built, although there was breakup of the grease into particles, there was absolutely no change in appearance of the grease either from a moisture or air content. Thus, the rotor form employing a lip and a noncritical orifice was 10 a complete failure. By removing the two-inch lip from the rotor and closing the orifice between the shrouding disk and accelerating disk in the rotor to one one-hundredth inch, I was able to process grease from a brown, 15 muddy stage to a bright, dark blue-green appearance by a single pass through the polisher.

The following tables give specific data on greases processed through the inventive apparatus, the second example being the latter example set forth above.

70 The actual physical appearance of the mist particles emitted from the inventive rotor having the alignment of the disk lips and the critical orifice as it passes from

the periphery of the rotor to the vessel wall is as follows:

A uniform thin sheet is discharged from the rotor at a high velocity and remains in an unbroken sheet for approximately one inch travel. At this point, the sheet breaks into small particles which continue to travel at a high velocity and they then coalesce in the knuckle radius of the polisher shell.

The physical appearance of grease passing from an aligned lip rotor having an excessive opening therein is as follows:

The discharge from the rotor is in bands with a thickness determined by the orifice opening and the width of the bands determined by the feed rate and velocity discharge from the rotor. In normal operation, these bands are about one inch wide and do not have a tendency to break into small particle sizes in their path from the rotor to the knuckle radius of the shell.

The physical appearance of grease passing from a rotor having an extension of the lip of either disk or such extension and an excessive orifice is as follows:

In this instance the discharge from the rotor has a nonuniformity of thickness which is created by shock waves that travel over the extended lip and increase in magnitude as they approach the periphery and further discharge from the rotor in bands that do not break into small particles in its path from the rotor lip to the coalescing knuckle.

Thus it is obvious that the inventive rotor having aligned lips and a critical orifice size actually demonstrates physically the smooth breakdown of the fluid into mist particles of micro dimensions which pass smoothly without shock waves from the inventive rotor to the vessel wall, thus permitting stripping of the volatiles during this passage.

The modifications of the invention illustrated in FIGS. 4-6 show grease polishers employing spray heads which are nonrotating. FIGS. 4 and 5 illustrate such a non-rotating spray head wherein a diaphragm bellows controls the orifice gap through which the grease is forced by pressure from the charge pump. By regulating the pressure within the diaphragm either from the grease feeding line or from an auxiliary pressure supply, the thickness of the film discharging from the rotor can be regulated. The modification of FIG. 6 shows a spray head arrangement employing springs to regulate the orifice discharge which employs limit stops to regulate the orifice discharge which employs limit stops to regulate the minimum orifice.

Referring then first to FIGS. 4 and 5, at 40 is shown a vessel having an upper portion of its wall inclined both upwardly and inwardly relative the interior of the vessel, a limited portion of the side walls relatively vertical and a lower wall portion inclined both downwardly and inwardly relative the interior of the vessel. These wall portions are shown at 40a, 40b and 40c, respectively. Referring particularly to FIG. 5, opening 41 is formed in the top center portion of the vessel shell 40 and mounting plate 42 having central opening 43 therein is fixed to the enlarged portion 41a of opening 41 by bolts 44. Shrouding disk 45 is fitted by its upwardly extending portion 46 into opening 43. L-fitting 47 has peripheral flange 48 at its lower end which is engaged by bolts 49 which also engage threaded openings 50 in the upper flange portion 51 of the shrouding disk 45. Vanes 52 are fixed in the throats of shrouding disk 45 and L-fitting 47. Feed inlet 53 extends laterally from L-fitting 47. Opening 54 is formed in the upper central portion of the L-fitting 47. Mount 55 is fixed by bolts 56 to the top of the L-fitting 47. Diaphragm housing 57 has upper and lower portions 58 and 59 fixed to one another by bolts 60 engaging flanges thereon and diaphragm 61 is also positioned between the two portions 58 and 59 and engaged by the flanges thereon. Input opening 62 in upper diaphragm por-

tion 58 has threaded input fitting 63 therein with pressure medium feed line 64 attached thereto. Shaft 65 extends through the diaphragm and is engaged therethrough by nuts and washers 66 and 67 on the threaded upper end thereof. Opening 68 in diaphragm portion 59 permits the extension of shaft 68 downwardly therethrough, the shaft extending also through opening 54 in L-fitting 47 and passing through sealing gland assembly 69 between the diaphragm and the L-fitting. Shaft 65 has an enlarged portion 65a below the opening 54 which extends centrally of the L-fitting opening and the shrouding disk upper portion 46 to engage bottom disk 70 whose outer edge is substantially vertically in line with the outer edge 45a of the shrouding disk. Application of greater pressure within the upper diaphragm portion 58 will force diaphragm 61 downwardly carrying shaft 65 therewith to move the shrouding and lower disc edges away from one another to increase the gap therebetween. The enlarged portion 65a of the shaft 65 abutting the top of the L-fitting 47 limits the upward motion of the lower disc 70. Secondary pressure line 71 engages fitting 72 threaded into opening 73 in the lower diaphragm portion 59 to aid in regulating the position of the diaphragm 61. The diaphragm assembly is fixed to the mounting 55 by bolts 74. Vacuum exhaust take-off 75 preferably, but optionally, extends to the wall 40c of the vessel 40 with its intake end positioned centrally under the lower disk 70 as seen in FIG. 5. The attachment fitting 76 on the outer end thereof may be coupled with any suitable exhaust line.

Referring now to FIG. 6, the like parts of the evacuation vessel are numbered like FIGS. 4 and 5. The shrouding disk in this construction is exactly the same as that shown in the modification of FIG. 5 and thus is like numbered as well. A slight change lies in the provision of openings 77 and bolt abutments 78 in the outer edge of the shrouding disk. An L-fitting similar to that of FIG. 5 is provided attached to the upper face of plate 42 and thus is numbered alike as are its attaching parts. However, the difference in this L-fitting lies in that there is no central upper opening 54 for the extension therethrough of a shaft attached to the lower disk. In this modification, the lower disk 79 having openings 80 arranged peripherally of its outer edge to match opening 77 in the shrouding disk is fixed relative the shrouding disk by two constructions. In the first place, limit stops 81 limit the closeness allowed of the two disks while bolts 82 extend through openings 77 and 80 and have springs 83 encircling the bolts and regulated in tension against the underside of the lower disk by nuts and washers 84 and 85 threaded on the lower ends of the bolts 82. The upper heads of the bolts 82 as shown at 82a rest on the leveling abutment 78 formed on the shrouding disk. The vacuum take-off in this construction is the same as in the previous construction and thus is like numbered. Steam or any other inert gas may be supplied to the vessels containing the apparatus of FIGS. 5 and 6 through pipes and may be introduced through hollow perforated rings 86 (FIG. 4) on the opposite side of the disk from vacuum line 76.

The difference in operation between the two units lies only in the manner of regulating the opening between the upper and lower disks in the spraying devices. Lower disk 79 has upwardly extending central portion 86 to guide the input viscous fluid uniformly outwardly in the channel 87 formed between the two disks. The required pressure for forcing the viscous fluids outwardly between the aligned edges 45a and 70a of both the modifications of FIG. 6 and FIG. 5 depend largely on the viscosity of the liquids. The pressure should be sufficient to drive the material outwardly through the orifice between the two disks to impinge at high velocity on the knuckle radius 40a of the vessel 40. The crucial range of orifice gap must be maintained within the two one-thousandths of an inch to fifteen one-thousandths of an inch range previously set

forth relative the rotor modification. Results obtained with the modification shown in FIGS. 5 and 6 are the same as those set forth relative the rotating device. The description of the appearance of the film discharged from the inventive rotor is the same applied to the film discharged from the modification of FIGS. 5 and 6.

From my experimental work and observations, I conclude that the orifice size employed in the rotating and nonrotating spraying devices disclosed above is valid over the range given. However, within this range, the smaller the orifice for a given feed stock, the higher the efficiency of the spraying device insofar as dehydration is concerned. On gas oils and very low viscosity lube oils, it would appear that an orifice in the range of three-thousandths inch to five-thousandths inch would be practical for commercial application. This would also be true when handling transformer oils. When handling medicinal oils having a viscosity of, say, 400 SSU at 100° F., the orifice would optimally be six-thousandths inch or less. On lube stocks, eight-thousandths inch would appear to be optimum for an orifice size and, in higher viscosity materials such as grease and sulfonates, it has appeared that the maximum permissible orifice should be less than fifteen-thousandths inch. In the transformer oils, a residual water content of five ten-thousandths percent is permissible. In medicinal oils, a residual water content of 0.005 percent is permissible and, in lube oils, the permissible water content is less than 0.01 percent. Greases are allowed by the industry to have a residual water content of from 0.5 to 1.5 percent while sulfonates may not exceed .05 percent residual water. The above optimum orifices refer to these requirements. Thus, transformer oils may employ an orifice from two-thousandths inch to four-thousandths inch, medicinal oils orifices from two-thousandths inch to six-thousandths inch, lube oil from two-thousandths inch to eight-thousandths inch and greases and sulfonates from two-thousandths to fifteen-thousandths inch. The above data indicates that a selected orifice width in said range is lesser for higher viscosity liquids and greater for lower viscosity liquids being treated, in order to achieve comparable results in dehydration and in the interest of higher efficiency.

In the case of the commercial size flash evaporators handling lube stocks with an extended lip, the discharge from the rotor is very definitely uneven and it appears that the majority of the material being discharged from the rotor is coming in heavy strings projected from the rotor vanes. In other words, from a visual inspection, it appears that the discharge is coming off the rotor similarly to that which would be expected from a rotor with drilled holes except that there is a substantial trailing edge to each discharge stream. In the case of grease, the discharge is entirely different in that severe shock waves are

imposed on the fluid flowing across the extended lip and, in this instance, it appears that the flow comes off as waves on the sea shore. This flow has been substantiated by taking a spatula and passing perpendicularly through the discharge film with the resultant deposit on the spatula being extremely corrugated.

Thus it is seen that by providing both rotating and nonrotating spray devices with aligned lips and severely limited orifices, I have been able to solve dehydrating and deaerating problems not previously solved by the art. I have provided new results never before accomplished.

From the foregoing it will be seen that this invention is one well adapted to attain all of the ends and objects hereinabove set forth, together with other advantages which are obvious and which are inherent to the structure.

It will be understood that certain features and sub-combinations are of utility and may be employed without reference to other features and subcombinations. This is contemplated by and is within the scope of the claim.

As many possible embodiments may be made of the invention without departing from the scope thereof, it is to be understood that all material hereinabove set forth or shown in the drawings is to be interpreted as illustrative and not in a limiting sense.

Having thus described my invention, I claim:

An atomizing rotor for treating a liquid containing at least two constituents of differing volatility, one more volatile than any other, comprising a pair of coaxially aligned rotatable discs spaced apart to form a narrow annular space therebetween, which tapers from a thicker throat portion to a narrow orifice having a width no greater than .015 inch and no less than .002 inch defined by the aligned peripheral lips of the discs, means rigidly fixing said discs together for rotation together at a given fixed spacing from one another within said range, the selected orifice width in said range being lesser for higher viscosity liquids and greater for lower viscosity liquids being treated to achieve comparable results, means for feeding said liquid between said discs into said annular space, and means for simultaneously rotating said discs about their common axis.
